UNITED STATES PATENT OFFICE.

LEROY J. HEFFRON, OF LESTERSHIRE, NEW YORK.

DESIGN FOR A WORK-STAND.

No. 39,684.

Specification for Design.

Patented Dec. 8, 1908.

Application filed August 7, 1908. Serial No. 447,486. Term of patent 14 years.

To all whom it may concern:

Be it known that I, LEROY J. HEFFRON, a citizen of the United States, residing at Lestershire, New York, have invented a new, original, and ornamental Design for a Work-Stand, of which the following is a specification, reference being had to the accompanying drawing, forming a part thereof.

The figure shows the work stand in perspective.

The ornamental design consists of a receptacle A, supported upon legs B, which ex-

tend above the line of the receptacle, a second receptacle C being located at the top, and this receptacle supports a spool table or holder D. Supporting hooks appear on the outer periphery of the upper receptacle.

I claim:

The ornamental design for a work stand as shown and described.

LEROY J. HEFFRON.
